UNITED STATES PATENT OFFICE.

JOHN A. FALVEY, OF DETROIT, MICHIGAN.

DESIGN FOR A POST CARD OR SIMILAR ARTICLE.

Application filed July 12, 1928. Serial No. 27,466. Term of patent 14 years.

To all whom it may concern:

Be it known that I, JOHN A. FALVEY, a citizen of the United States, residing at 751 Collingwood Avenue, Detroit, in the county of Wayne and State of Michigan, have invented a new, original, and ornamental Design for a Post Card or Similar Article, of which the following is a specification, reference being had to the accompanying drawing, forming part thereof.

The figure is a plan view of a post card or similar article, showing my new design.

I claim:

The ornamental design for a post card or similar article, as shown.

JOHN A. FALVEY.
